UNITED STATES PATENT OFFICE

125,154

DESIGN FOR A SEAT END STANDARD

Onnie Mankki, Cleveland Heights, Ohio, assignor
to American Seating Company, Grand Rapids, Mich., a corporation of New Jersey

Application April 22, 1940, Serial No. 91,852

Term of patent 7 years

To all whom it may concern:

Be it known that I, Onnie Mankki, a citizen of the United States, residing at Cleveland Heights, in the county of Cuyahoga and State of Ohio, have invented a new, original, and ornamental Design for a Seat End Standard, of which the following is a specification, reference being had to the accompanying drawing, forming a part thereof, in which—

Figure 1 is a side elevational view of a seat end
standard showing my new design;

Figure 2 is a rear side elevational view of the seat end standard;

Figure 3 is an enlarged sectional view thereof on line 3—3 of Figure 1; and

Figure 4 is a sectional view on line 4—4 of Figure 1.

The characteristic features of my design reside
in the portions shown in solid lines in the drawing.

I claim:

The ornamental design for a seat end standard,
as shown and described.

ONNIE MANKKI.
